TREATMENT OF TALL OIL

Nicholas L. Kalman, deceased, late of Rutherford, N. J., by Anna Kalman, executrix, Newark, N. J., assignor to Ridbo Laboratories, Inc., Paterson, N. J., a corporation of New Jersey

No Drawing. Application June 9, 1945,
Serial No. 598,643

10 Claims. (Cl. 260—97.5)

1

This invention relates to treatment of tall oil and is especially concerned with a method by which crude tall oil may be treated to derive therefrom an oily product having a number of altered and improved physical and chemical characteristics which adapt the product to a number of commercial uses for which the crude material is not well suited.

As is known, tall oil is a waste or by-product of the process of paper manufacture, the crude tall oil comprising a sludgy mass containing fatty acid and rosin constituents, the latter of which manifests a marked tendency to crystallize, and the mass being characterized by a particularly obnoxious odor and a very dark color.

Aside from the dirt, impurities, color bodies, sterols, etc., crude tall oil consists essentially of rosin acids and of fatty acids, the latter of which are similar in general properties to the fatty acids of semi-drying fatty oils. The rosin and fatty acid constituents taken together comprise roughly 90% of the tall oil, and each of these two major constituents comprises approximately one-half of the material, excluding the impurities, etc.

A number of treatment processes have been proposed for refining, purifying and the like, of crude tall oil and in some cases the prior treatments improved the color, in others they improved the odor and in still others the tendency to crystallize has been more or less completely overcome. However, although prior known treatments have been effective in one or two of the respects just mentioned, no one prior treatment has been thoroughly effective in all three of the respects referred to. In addition, for certain purposes it is of distinct advantage to alter the chemical characteristics of crude tall oil, and the process of the present invention is not only highly effective in eliminating sludging and improving color and odor but additionally brings about certain other changes of desirable character as will further appear.

Briefly, in a typical treatment according to the invention, the tall oil is heated for a period of about three hours at about 300° C. in the presence of ortho-phosphoric acid, after which the tall oil is distilled, preferably under high vacuum. In this typical treatment the phosphoric acid performs several functions. In the first place, the phosphoric acid reacts with various impurities, color bodies, etc., to convert the same to a form in which they are non-distillable. The phosphoric acid also serves as an agent promoting decarboxylation of rosin acids present. The subsequent distillation, which in a typical case is ef-

2

fected at an absolute pressure in the neighborhood of 5 mm. Hg and is carried up to a temperature of about 225° C., results in the distilling over of the major portion of the fatty acid, decarboxylated rosin and the remaining rosin acids, leaving a residue consisting of substantially undistillable reaction products of the phosphoric acid with impurities, color bodies, polymers, etc. The distillate, in a typical case, comprises about 70 to 80% of the crude tall oil taken for treatment, the distillate being an oily substance of pale yellow color and fatty or fruity odor. In many cases the distillate manifests no tendency to develop crystals even after standing for extended periods of time. The treatment conditions may be controlled to vary the extent of decarboxylation of rosin acids. Preferably the decarboxylation is such as to yield a product having an acid value not above about 130, which compares with 165-170 for crude tall oil.

Because of various of the characteristics mentioned above, the total distillate or separated constituents thereof are well adapted to many commercial uses such, for example, as plasticizers for plastics, coating compositions, etc.

Another important advantage of the product produced in accordance with the method of this invention is that the fatty acid component of the distillate is essentially unchanged by the treatment, and therefore, upon separation of the acid constituents from the others, this component can be used for any purposes for which semi-drying fatty acids are useful. The rosin hydrocarbon component is also useful for many industrial purposes.

Of the treating agents which may be employed according to this invention, ortho-phosphoric acid or its anhydride constitutes a typical and especially effective treating agent. However, other phosphorus compounds may also be used, particularly the acids, oxides, sulfides, halides (especially chlorides), and oxychlorides. Typical agents are as follows:

45	Pyro-phosphoric acid
	Hypo-phosphorous acid
	Ortho-phosphorous acid
	Phosphorus pentasulfide
	Phosphorus trichloride
	Phosphorus pentachloride
	Phosphorus oxychloride

It may be mentioned that meta-phosphoric acid may also be employed in some cases but this particular compound requires exceptionally severe treatment conditions in order to effect any

substantial decarboxylation of rosin acids present.

The quantity of treatment agent employed may vary from about 0.5% up to about 10%, or somewhat higher, although increase of the quantity above about 10% ordinarily does not manifest any further improvement in decarboxylation or decolorizing action. At the higher percentages of reagent used the temperature of pretreatment should preferably be kept somewhat below 300° C. Usually from about 1% to 3%, for instance 10 2%, is sufficient to bring about quite extensive changes in properties of the crude tall oil. It is of advantage not to exceed about 5%, since above this percentage a greater degree of polymerization takes place, thereby reducing the distillate yield.

The treatment temperature to be employed in the presence of the treating agent may vary anywhere from about 250° C. to about 350° C., a 15 particularly effective range being from 275° C. to

EXAMPLES

COMPARATIVE EXAMPLES 1-9

In this group of examples crude tall oil was first pretreated with a number of different phosphorus compounds, 2% of the treating agent being used (except for the two examples noted in the following table). The treatment temperature in each example was 300° C. and the time of treatment was 3 hours. In each case distillation was effected at a pressure between about 1 and 8 mm. Hg, the temperature being carried up to the neighborhood of 200° C. or somewhat higher.

Various of the characteristics of the products 15 of these examples are given in Table I just below. In the table there is also included reference to a "blank" experiment, representing a heat treatment and distillation effected without the employment of a treating agent. Still further, at 20 the bottom of the table data is given for crude untreated tall oil, for purposes of comparison.

Table I.—Various treating agents

Ex. No.	Agent	Acid #	Color	Odor	Iodine #
Blank	None	160	Light Amber	Acidic	Hübl 100.
1	Ortho-phosphoric acid (85%)	132	Pale Yellow	Fatty	Hübl 88.
2	Pyro-phosphoric acid	101	Yellow	do	Hübl 100.
3	Hypo-phosphorous acid	94.8	do	do	Hübl 98.
4	Ortho-phosphorous acid	79.7	do	do	Wijl 160.
5	Phosphorus pentoxide (phosphorus anhydride)	66	do	do	Wijl 153.
6	Phosphorus pentasulfide	83.8	Pale Yellow	do	Wijl 116.
7	Phosphorus trichloride	92.6	do	do	Wijl 142.
8	Phosphorus pentachloride	133.8	do	do	Hübl 113.
9	Phosphorus oxychloride	110	do	do	Wijl 156.
	Crude-Untreated	165	Black	Foul	Hübl 130.

¹ 2.5% agent used—all others 2%.

325° C. From about 1 to 5 hours is ordinarily sufficient for the time of treatment, i. e., for the time of treatment preceding distillation.

In effecting distillation, the pretreated material is heated under vacuum, preferably below about 20 mm. Hg. A small forerun is usually taken and set aside, since it contains some water and a constituent of foul odor. The main distillate, at from 1-10 mm. Hg comes over between 40 about 130° C. and about 240° C.

As an alternative to the procedure of first pretreating the tall oil with the phosphoric acid for a period of several hours and thereafter distilling, the distillation may be commenced at or toward the beginning of the heat treatment with 50

The products of all of the above examples were clear oils and many showed no tendency to crystallize even after prolonged standing.

COMPARATIVE EXAMPLES 10-13

This group of examples were all performed under similar conditions except for a variation in the percentage of ortho-phosphoric acid used. Other minor variations in conditions of treatment are indicated in Table II just below.

In general the examples of this group were carried out in the same manner as described above in connection with Examples 1-9 inclusive. The data for Example 1 from Table I is also included in Table II for comparison.

Table II.—Variation in percent of treating agent ortho-phosphoric acid

Ex. No.	Per cent	Time, hrs.	Acid #	Color	Odor	Iodine #
Blank	None	4	160	Light Amber	Acidic	Hübl 100.
10	1	3	121	Yellow	Fatty	Wijl 168.
11	2	3	132	Pale Yellow	do	Hübl 86.
12	3	5	105	Yellow	do	Hübl 130.
13	5	4	60	do	do	Wijl 146.
	7	5	90	do	Faint T. O.	Hübl 112.

¹ Pretreated at 275° C.—all others at 300° C.

phosphoric acid, for example when the temperature has been raised to about 150° C., the distillation being continued during rise in temperature to about 240° C. The improvement in color and odor and the extent of decarboxylation, however, when proceeding in this way are not as great as where the tall oil is pretreated for several hours prior to the distillation. The treatment is therefore the preferred practice.

COMPARATIVE EXAMPLE 14

In this example the crude tall oil was pretreated for 6 hours at 250° C. with 2% of ortho-phosphoric acid. The subsequent distillation (effected in the manner above described) yielded a yellow oily product, free from crystals or tendency to crystallize and of fatty odor having an acid number of 128 and a Hübl iodine number of

5
COMPARATIVE EXAMPLE 15

This example illustrates the alternative treatment procedure where distillation is commenced without any extended period of pretreatment with the treating agent. The treating agent employed was ortho-phosphoric acid, 2% being used and the vacuum was applied for distillation in the neighborhood of 150° C., the temperature of the distillate vapor being carried up to 228° C. The treatment was effected at a pressure of 1-2 mm. Hg and yielded a distillate comprising a clear, yellow oily material of fatty odor, having an acid value of 95 and Hübl iodine value of 130.

It is claimed:

1. A method for treating tall oil comprising heating the tall oil in the presence of from 0.5% to 10% of an agent selected from the class consisting of phosphorous acids, oxides, sulfides, chlorides, and oxychlorides, at a temperature between about 250° C. and about 350° C., and distilling the volatile constituents of tall oil to recover a product essentially consisting of a mixture of fatty acids and rosin hydrocarbons. 15
2. A method for treating tall oil comprising heating the tall oil in the presence of from 1% to 3% of an agent selected from the class consisting of phosphorous acids, oxides, sulfides, chlorides, and oxychlorides, at a temperature between about 250° C. and about 350° C., and distilling the volatile constituents of tall oil to recover a product essentially consisting of a mixture of fatty acids and rosin hydrocarbons. 20
3. A method according to claim 2 in which 25
4. A method according to claim 2 in which the tall oil is treated with said phosphorus agent for at least 1 hour prior to the distillation thereof. 30
5. A method according to claim 2 in which the treating agent is a phosphorus acid.
6. A method according to claim 2 in which the treating agent is a phosphorus oxide.
7. A method according to claim 2 in which the treating agent is a phosphorus chloride.
8. A method according to claim 2 in which the treating agent is ortho-phosphoric acid.
9. A method according to claim 2 in which the treating agent is phosphorus pentoxide.
10. A method according to claim 2 in which the treating agent is phosphorus trichloride.

ANNA KALMAN,
Executrix of the Estate of Nicholas L. Kalman,
Deceased.
